(57) **CLAIM**

The ornamental design for an electrical connector as shown and described.

DESCRIPTION

FIG. 1 is a front perspective view of an electrical connector according to the present invention.

FIG. 2 is a rear perspective view of the electrical connector of FIG. 1.

FIG. 3 is a front view of the electrical connector of FIG. 1. FIG. 4 is a rear view of the electrical connector of FIG. 1. FIG. 5 is a left side view of the electrical connector of FIG. 1.

FIG. 6 is a right side view of the electrical connector of FIG. 1.

FIG. 7 is a top view of the electrical connector of FIG. 1; and,

FIG. 8 is a bottom view of the electrical connector of FIG. 1.

The electrical connector housing, which is formed of two parts, can have the same or different colors from one another, in particular being transparent, and the cable insert portion of the housing can be transparent or colored. The claimed design does not claim a particular color or transparency. The broken lines in the drawings illustrate portions of the electrical connector that form no part of the claimed design.
